SOLING MACHINE

Filed April 16, 1931

INVENTORS:
Adolf Ehresmann
Antony Strelbel

UNITED STATES PATENT OFFICE

ADAM EHRESMANN AND LUDWIG STREIBEL, OF KARLSRUHE, GERMANY

SOLING MACHINE

Application filed April 16, 1931, Serial No. 530,610, and in Germany April 28, 1930.

We have filed an application for patent in Germany, April 28th, 1930.

Our invention relates to soling machines, in which the tool for feeding the work is provided with a knife for cutting the channel for the stitches, this knife being so disposed that in the ascending movement of the feeder it cuts the said channel at right angles to the surface of the sole, into the underside of the sole, which is pressed firmly against the stitch plate by the presser foot.

According to the invention the stitch plate is carried by a slider adapted to be moved up and down and fixed on the front of the frame, so that by moving this slider vertically the stitch plate can be adjusted to cut channels of different depths.

Our invention is illustrated by way of example in the accompanying drawing in which Figure 1 shows the parts to be considered of a machine according to the invention in front elevation; Figure 2 is a corresponding plan one of the two screws *k* and handles *l* shown in Figure 1 being removed for the purpose of clearly showing the scale *r*; and Figure 3 shows a detail part in vertical section along the line A—B of Figure 1.

Below the presser foot *a* and the stitch plate *b* there is disposed the free end of a lever arm *c*, to which is secured a steel knife projecting upwardly through the slot of the stitch plate. This knife is provided at the top with a stepped edge *d*, *e*; the higher and narrower part *d* of this knife edge forms the tool for feeding the work, while the lower and wider part *e* forms the channelling knife. While the presser foot holds the work firmly on the stitch plate, the knife is moved upwards to such an extent that not only the higher part *d* of its cutting edge but also the lower part *e* of the same penetrates into the work, wherein the part *d* pierces a stitch hole and the part *e* cuts a piece of a channel into the under side of the sole resting on the stitch plate. After the presser foot has been lifted, the knife is moved to the left to the extent of a stitch and thus feeds the work. The presser foot and the knife are now moved downwards so that the presser foot again presses the work upon the stitch plate while the parts *d* and

e of the knife edge leave the work. Thereafter the knife is moved back to the right and again upwards so that the part *d* pierces a further stitch hole and the part *e* cuts a further piece of the channel directly joining the preceding piece. The stitch plate *b* is screwed to the upper part of a frame-shaped slider *f*, which is adapted for vertical reciprocatory movement on the vertical flat front face of the front part *h* of the machine frame which houses the shuttle box *g*. Two pins *i* and four round-headed screws *k* engaging, through slots in the slider, in holes in the part *h*, serve to guide the slider in a straight line in its up-and-down movement. The two upper screws *k* are each provided with a handle *l*, so that they can be turned directly by hand. In turning them inwardly the slider *f* is clamped firmly between their heads and the part *h*, so that this slider together with the stitch plate *b* is retained in its adjusted position.

The slider *f* and the stitch plate *b* may be moved up and down by means of a second slider *m*, bent from sheet metal, which is adapted to reciprocate in front of the lower part of the slider *f*, horizontally on the base plate *n* of the frame, and transversely to the spindle of the shuttle box *g*. This second slider has two feet *o*, the upwardly projecting rear flange of which forms a wedge *p*. Each of these wedges engages in a wedge-shaped groove on the rear side of the slider *f*, thus holding the slider *m* in position and, when this is horizontally displaced, effecting the vertical movement of the slider *f*. An upwardly extending projection *q* on the left end of the slider *m* limits the movement to the right of the slider *m* by striking against the lateral edge of the slider *f*, and therefore also limits the upward movement of the slider *f* and the stitch plate *b* (indicated by broken lines in Figure 1), while, in conjunction with the lateral edge of the slider *f*, a scale *r*, provided on the upper side of the slider *m*, indicates the elevation of the stitch plate *b* and therefore the depth of the channel which is cut by the knife *e* into the sole resting on the stitch plate.

What we claim as our invention and desire to secure by Letters Patent is:

1. In a soling machine the combination of a machine frame having a bed plate, a presser foot, a stitch plate disposed below said presser foot and provided with a slot, a lever arm, the free end of said arm being disposed below said stitch plate, a knife forming both a feeding and a channelling tool, said knife being secured to the free end of said arm and projecting upwardly through said slot, a slider carrying said stitch plate and being disposed on the front of said frame and adapted to be moved thereon up and down, a second slider disposed in front of said frame and on said bed plate and adapted to be moved horizontally and to effect the vertical movement of the first said slider, and means for fixing the latter.
2. In a soling machine the combination of a machine frame having a bed plate, a presser foot, a stitch plate disposed below said presser foot and provided with a slot, a lever arm, the free end of said arm being disposed below said stitch plate, a knife forming both a feeding and a channelling tool, said knife being secured to the free end of said arm and projecting upwardly through said slot, a slider carrying said stitch plate and being disposed on the front of said frame and adapted to be moved thereon up and down, a second slider disposed in front of said frame and on said bed plate, wedge shaped grooves in the first said slider, and wedges on said second slider engaging in said grooves, the said second slider being adapted to be moved horizontally so as to move the first said slider vertically by said wedges coacting with said wedge shaped grooves, and means for fixing the first said slider.

In testimony whereof we affix our signatures.

ADAM EHRESMANN.
LUDWIG STREIBEL.
